CLAIM

I claim the ornamental design for a soup bar, as shown and described.

DESCRIPTION

FIG. 1 is a top left front perspective view of a soup bar showing our new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken line portion of the figure drawings is included to show portions of the article that form no part of the claimed design.

1 Claim, 5 Drawing Sheets
